[57] ABSTRACT

A drying apparatus which has a slit for ejecting an air jet, a mechanism for carrying a material so that the surface of the material being dried passes near the slit, and blade plates extending generally in parallel with the surface being dried in the direction of movement of the material by the slit, and in the direction opposite thereto.

FIG. 5

FIG. 6

FIG. 7

DRYING APPARATUS

BACKGROUND OF THE INVENTION

This invention relates to an apparatus for drying material with an air stream and, in particular for drying an electrophotographic material or silver halide photographic material.

The conventional drying apparatus using an air jet has many disadvantages as will be described with reference to the conventional apparatus shown in FIG. 1. In FIG. 1, which shows a longitudinal sectional side view of the conventional drying apparatus for sheets or web material using an air stream, there is shown a material 10 to be dried such as an electrophotographic material moistened upon treating by a liquid developing process or silver halide photographic material moistened with water after developing treatment. There is also shown an air supply pipe 11, an air jet injection slit 12, the place 13 directly under the slit 12 where the air jet is strongest, an air stream 14 indicating that the ejected air jet is expanding, and a drive roller 16 for driving the material 10 to be dried in the direction designated by an arrow 15. The air is fed into the air supply pipe by an air compressor or fan. When the roller 16 is rotated clockwise, the material 10 is driven in the direction designated by arrow 15. The liquid which moistens the surface of the material 10 is swept in the direction designated by arrow 17 by the air jet. It is common that a very thin liquid is retained on the surface of the material 10 even if the liquid on the surface of the material 10 is swept by the air jet. However, this thin liquid film is dried and evaporated by the air jet. This thin liquid film is retained in the event that the surface of the material 10 is moistened with a wettable liquid. For example, the thin liquid film is retained when a material having a hydrophilic surface is moistened with water or when a material having an oilphilic surface is moistened with oil. On the contrary, the thin liquid film is not retained when the hydrophilic surface is moistened with oil or when the oilphilic surface is moistened with water.

In the apparatus shown in FIG. 1, the speed of the air jet is very high at the place 13 directly under the slit 12, but the air stream can freely expand in the space away from the place 13 as shown by numeral 14, and accordingly the speed of the air jet becomes abruptly small. As a result, the air stream away from the place 13 has a small capability to sweep the liquid on the surface of the material 10 and also has small capability to dry the liquid film retained on the surface of the material 10. In other words, the drying speed is low. Therefore, the speed for driving the material 10 in the direction designated by arrow 15 cannot be substantially increased. The simplest method for increasing the drying speed in the apparatus shown in FIG. 1 is to increase the air amount supplied into the pipe 11 thereby increasing the speed of the air jet from the slit 12. However, it incorporates the following disadvantages.

First in order to increase the air supply amount, the capacity of the air compressor or the fan must be increased with the result that the air supplying device becomes large. Second, if the speed of the air jet becomes high, the sound generated at the air jet injection slit 11 is enhanced to introduce a large noise within the drying apparatus. Third, the speed of the air stream at the place 13 directly under the slit becomes locally very strong with the result that it undesirably affects the ma-

terial. For example, it is thought that the toner image formed on the surface of the electrophotographic material can be damaged. It is well known that the toner image obtained by the liquid developing process is mechanically very weak before it is fixed, particularly while it is moistened, and thus tends to be broken. Therefore, if an excessively high speed air jet is used, the toner image tends to be damaged. Accordingly, it is desirable to avoid an increase in the speed of the air jet.

SUMMARY OF THE INVENTION

This invention contemplates eliminating the aforementioned disadvantages of the conventional drying apparatus and providing a superior drying apparatus.

According to one aspect of this invention, there is provided a drying apparatus which comprises a slit for ejecting an air jet, a mechanism for carrying a material so that the surface of the material being dried passes near the slit, and blade plates extending generally in parallel with the surface being dried in the direction of movement of the material by the slit and in the direction opposite thereto, or in at least one of these directions.

DETAILED DESCRIPTION OF PREFERRED EMBODIMENTS

These and other objects, features and advantages of this invention will become apparent from the following description taken in conjunction with the accompanying drawings, in which:

FIG. 1 is a longitudinal sectional side view of the conventional drying apparatus for sheets or web material using an air stream;

FIGS. 2 to 7 show longitudinal sectional side views of the embodiments of the drying apparatus of this invention.

DETAILED DESCRIPTION OF PREFERRED EMBODIMENTS

Reference is now made to the drawings, particularly to FIGS. 2 to 7, which show the embodiments of this invention.

In FIG. 2, there is shown the essential part of one embodiment of the drying apparatus of the invention in principle.

Reference numerals 20 and 21 illustrate blades extended at both sides of a slit 12, extending generally in parallel with the surface of the material 10. The lengths of the blades 20 and 21 in the direction designated by arrow 15 may be properly selected, but the larger the size of the blades, the faster the speed. However, when the drying apparatus is contemplated to be compact, this length may be properly designed in relation with the size of the apparatus. The widths of the blades 20 and 21 perpendicular to the arrow 15 may be generally similar to the length of the slit perpendicular to the arrow 15. If the material 10 is driven in the direction designated by arrow 15 under the slit 12, the air jet ejected from the slit 12 passes through the gaps 22 and 24 between the material 10 and the blades 20 and 21 to be expanded in the space at the end of the blades as shown by 23 and 25 in FIG. 2. As shown in FIG. 2, the air jet discharged from the slit 12 does not expand at once in the space, but expands after passing the long passages 22 and 24. Therefore, in comparison with the apparatus shown in FIG. 1, the time the air stream at

high speed contacts with the surface of the material 10 becomes long with the result that the capability to sweep the liquid moisture on the surface of the material 10 and to dry the thin liquid film retained on the swept surface become quite large.

Referring now to FIG. 3, which shows the section of the essential part of the embodiment desirable in this invention, numerals 30 and 31 show a pair of feed rollers. The roller 30 has flanges at both ends thereof, and the material 10 is driven interleaved between the flanges and the roller 31. The roller surface 35 inside the flange of the roller 30 does not contact the material 10. This condition is particularly important in case the material 10 has a toner image on an electrophotographic material. That is, it prevents the toner image from being damaged by minimizing contact with the roller 30. The roller 32 maintains the distance between the surface of the material 10 and the slit constant similar to the roller 16 in FIG. 2. The rollers 33 and 34 are a pair of feed roller having the same function as that of the rollers 30 and 31, respectively. The roller 33 has flanges at both ends, and 36 shows the area inside the flanges. The material 10 is engaged with the flanges of the roller 33 and the roller 34 and fed in the direction designated by the arrow 15. The blades 20 and 21 extend front and rear on both sides thereof from the slit 12 and contact the rollers 30 and 33, respectively in order to prevent the air from leaking at the gap between the blade 20 and the roller 30 or between the blade 21 and the roller 33. In practice, the air may be leaked. The air supplied to the pipe 11 is ejected from the slit 12 to pass the gaps 22 and 24, and further through the gaps between the rollers 30 and 31, 33 and 34 and expanded in the free space as shown by 37 and 38 in the drawing. The apparatus shown in FIG. 3 is particularly proper for the material 10 being in sheet state. The dimensions and an example of the operation will now be described with concrete reference to numerals thereof as this embodiment of the apparatus. The outer diameters of the rollers 30 to 34 are 18 mm, the inside diameter of the rollers 30 and 33 and flanges or the diameter of the rollers 35 and 36 in FIG. 3 are 16.6 mm, and accordingly the thickness of the flange is 0.7 mm, the material of the rollers 30 to 34 being all stainless steel. The inner diameter of the pipe 11 is 14 mm, the thickness thereof 1.5 mm and the material thereof brass. The width of the slit 12 is 1 mm, the gap between the blades 20 and 21 and the surface of the material 10 being 2 mm. The length of the lateral direction rightward and leftward of the blades 20 and 21 in the drawing are both 20 mm. The material 10 was driven at a speed of 5 cm per second in the direction designated by arrow 15, and the air supply amount to the pipe 11 was 2,800 liters per minute. However, in order to prevent the air from being leaked laterally (vertically in the drawing), side walls are provided at both sides. Under such conditions, the electrophotographic material is preferably preferably. When the blades 20 and 21 were not provided, the drying was insufficient.

FIG. 4 shows the section of the essential part of another preferred embodiment of the drying apparatus of this invention. Numeral 40 shows a drive roller for driving a web 41 around the roller, 41 a developer container, 43 a developing liquid filled therein, 44 and 45 are blades extended at both sides front and rear of the slit 12 parallel with the periphery of the roller 40, and

46 is a roller for changing the direction of the web. The air ejected from the slit passes through the gaps 47 and 48 to be expanded in the space as shown by 49 in the drawing. When the width of the slit 12, gaps 47 and 48, and driving speed of the web are selected similar to the embodiment in FIG. 3, the preferred result is obtained.

FIG. 5 shows the section of the essential part of a further embodiment of the drying apparatus of this invention. The apparatus shown in FIG. 5 has no corresponding blade 21 in FIG. 3. Instead, the pipe 11 contacts the roller 33 so as to reduce the air from being leaked between the gap of the pipe 11 and the roller 33. The other functions and parts are the same as those in the embodiment shown in FIG. 3. The object of this invention will be effectively performed by the apparatus which has only one blade at one side of the slit 12 as shown in FIG. 5. However, it is recognized that the embodiment of FIG. 3 results in a better effect than that of FIG. 5.

FIG. 6 is the section of the essential part of still another embodiment of this invention. Numeral 60 indicates flanges provided at both ends of the pipe 61 similar to the pipe 11 shown in FIG. 3, the flanges being freely rotatable. Numeral 62 is a slit provided at the lower end of the pipe 61 corresponding to the slit 12 in the drying apparatus shown in FIG. 3. Numerals 63 and 64 are blades provided at both ends of the slit 62 corresponding to the blades 20 and 21 in FIG. 3. In the embodiment shown in FIG. 3, the material 10 is depressed adjacent the roller 32 by the air jet ejected from the slit 12 but in FIG. 6, the material 10 is engaged by the flanges 60 and roller 32. Consequently, when the material 10 arrives under the slit, the possibility that the material 10 will prevent the turbulence of the air stream from passing through remote. More particularly, the drying apparatus in FIG. 6 is the embodiment where the passage of the material 10 becomes stable.

FIG. 7 shows the section of the essential part of still another embodiment of the drying apparatus of this invention. This apparatus has symmetrical structure to the material 10 for drying both the front and rear surface of the material at the same time.

What is claimed is:

1. A drying apparatus comprising (1), at least one air supply means including (a) a slit for ejecting an air jet onto a material having a developed image on the surface to be dried, said slit being disposed transverse to the direction of movement of the material, has been inserted, and (b) two blade plates respectively extending from the sides of the slit generally across the width of and in parallel with the surface to be dried, and two pairs of feed rollers for carrying the surface to be dried past the said slit where each pair is disposed on opposite sides of said material and on opposite sides of said slit, the feed rollers on the same side of said material as said blade plates having flanges at both ends thereof which contact said material at the approximate edges thereof, to thereby prevent said material from contacting said blade plate so that said image cannot be damaged by contact with said blade plates, and where said blade plates contact the feed rollers which are on the same side of said material as themselves to prevent the passage of said air jet therebetween.
2. A drying apparatus as in claim 1 where said at least one air supplying means includes a rotatable flange dis-

posed at each end of said slit to prevent said material from contacting said blade.

3. A drying apparatus as in claim 1 including a second air supply means symmetrically disposed on the side of said material opposite said at least one air supply means.

4. A drying apparatus comprising (1) at least one air supply means including (a) a slit for ejecting an air jet onto a material having a developed image on the surface to be dried, said slit being disposed transverse to the direction of movement of the material, has been inserted, and (b) at least one blade plate extending from one side of the slit generally across the width of and in parallel with the surface to be dried, and (2) at least

one pair of feed rollers for carrying the surface to be dried past the said slit, said pair of feed rollers being disposed on opposite sides of said material and adjacent one side of said slit the feed roller on the same side of said material as said blade plate having flanges at both ends thereof which contact said material at the approximate edges thereof to thereby prevent said material from contacting said blade plate so that said image cannot be damaged by contact with said blade plate, and where said air supplying means includes a rotatable flange disposed at each end of said slit to prevent said material from contacting said blade.
